E. GRIESBAUM.
AIR PUMP.

APPLICATION FILED AUG. 13, 1919.

1,341,460.

Patented May 25, 1920.

UNITED STATES PATENT OFFICE.

ERWIN GRIESBAUM, OF ST. LOUIS, MISSOURI.

AIR-PUMP.

1,341,460.

Specification of Letters Patent.

Patented May 25, 1920.

Application filed August 13, 1919. Serial No. 317,258.

To all whom it may concern:

Be it known that I, ERWIN GRIESBAUM, a citizen of the United States, residing in the city of St. Louis and State of Missouri, have 5 invented new and useful Improvements in Air-Pumps, of which the following is a specification, reference being had to the accompanying drawings.

The present invention relates to air pumps, 10 and especially to such pumps adapted for use in inflating automobile tires, or other pneumatic tires.

The primary object of the invention is to afford a simple, and practical method of constructing such pumps, whereby the pump may be readily assembled or disassembled for the purpose of repair, or replacing of parts.

Another object is to produce such pump 20 with certain novel features of construction in order to cheapen the cost of the pump and strengthen the structure thereof.

In the drawings

Figure 1 is a vertical, sectional detail 25 showing the mounting of one of the tube caps and air outlet valve;

Fig. 2 is a horizontal section taken on the line 2—2 in Fig. 1;

Fig. 3 is a perspective view of a complete 30 assembled pump;

Fig. 4 is a longitudinal section of the pump as shown in Fig. 3;

Fig. 5 is a detail showing a method of stamping out the foot from sheet metal. 35 Referring more particularly to the drawings, my invention consists of a relatively large tube 9 and a relatively small tube 10 located parallel to one another upon the foot or base 11. Said tubes are interiorly

40 connected at their base portion through an air channel 14, which may be formed in the base housing 37. Within the tubes 9 and 10 are mounted air compressing pistons 12 and 13 at the lower end of the piston rods 21

45 and 22. The piston in the larger tube 9 being adapted to force the air downwardly with the down stroke of the pump, while the piston in the smaller tube 10 is adapted to force the air upwardly with the up

50 stroke of the pump. The piston of the larger tube is composed of a leather washer 15 with its periphery inclined downwardly and locked between two metal washers 16 and 17, thus adapting the piston to 55 press air on the down stroke of the pump. To secure these washers in place, a pin 18

is inserted through the rod 21, at the lower end of which said piston is mounted, while the lower end 20 of the rod is riveted over. Similarly, the leather washer 23 of the 60 small piston 13 is positioned between the metal washers 24 and 25 with a pin 26 inserted through the piston rod 22 at the upper side of the piston and with the lower end 27 of the piston rod 22 being riveted 65 over. The leather washer 23 is positioned with its periphery upwardly inclined so as to adapt the piston to compress air on the up stroke of the pump. The top cap 28 is adapted to snugly fit over the top end of 70 the large tube 9, and is secured in place thereon by means of set screws 29. An air inlet port 45 is cut through said top cap 28. The top cap 30 is adapted for threaded engagement with the top of the small tube 10. 75 A double handle 31 is mounted at the top of the piston rods 21 and 22 by means of encircling ferrules 33 and 34 which are pinned to the upper ends of said rods by the pins 35 and 36. The base housing 37 may be 80 stamped from a single piece of metal so as to form housings for the lower ends of the tubes 9 and 10, in which housings they are mounted by means of set screws 38 and 39, or they may be threaded and thus secured in 85 place. This base housing 37 is so formed as to afford a connecting air passage 14 for connecting the interior of the tubes 9 and 10 at their lower end. The base or foot 11 is likewise stamped from a single piece of 90 sheet metal with annular flanges 41 and 42 turned upwardly and over to engage the outstanding flanges 43 and 44 of the base housing 37.

The top cap 30 acts also as a housing for 95 the packing washer 46, which washer slidingly engages the piston rod 22 and sets upon the upper end of the tube 10, being so formed and positioned that there is certain play between the said upper end of the tube 10 and the top cap 30. Transverse notches 47 and 48 are cut in the edges of said washers at diametrically opposite points, one for the purpose of permitting air to pass through the pump, and the other to engage 100 the pin 49 to prevent the washer turning. This washer is so positioned within the housing of the top cap 30 that one of the notches as 47 will stand in alinement with the mouth 52 of the outlet pipe 53, thus permitting the passage of air. A packing 105 50 surrounds the piston rod 22 between the

washer 46 and the cap 30. A ball valve 51 is mounted in the mouth 52 of the outlet pipe 53.

This pump is thus simply put together and may be quickly disassembled for repairing; the construction for housing the packing is quite simple compared to the pumps now on the market; and the method of mounting the handle and pistons is simple 10 yet strong.

While I have herein described a certain specific manner and method of constructing and assembling the elements of my invention, it is understood that I may vary from 15 the same in minor details, not departing from the spirit of my invention, so as best to construct a practical device for the purpose intended, as defined in the appended claims.

20 What I claim to be new and patentable is:

1. In combination with an air pump, a housing for the base thereof, same being stamped from a single piece of sheet metal;

an extended annular flange formed upon said housing; air channels formed in said housing to lead air in and out of the pump proper; and a foot portion likewise stamped from a single piece of sheet metal, and having outstanding flanges adapted to be turned up over the extended annular flange 25 30 on the housing, to lock the two together.

2. In combination with an air pump, a housing for the base thereof, same being stamped from a single piece of sheet metal; an extended annular flange formed upon 35 said housing; air channels formed in said housing to lead air in and out of the pump proper; a foot-portion likewise stamped from a single piece of sheet metal, and having outstanding flanges adapted to be turned 40 up over the extended annular flange on the housing, to lock the two together; and means for securing the housing to the pump proper.

ERWIN GRIESBAUM.
